UNITED STATES PATENT OFFICE.

JOSEPH MALICKI, OF CHICAGO, ILLINOIS, ASSIGNOR TO WALTER B. TEMPLETON, OF CHICAGO, ILLINOIS.

CLOSURE FASTENER.

Application filed May 3, 1923. Serial No. 636,343.

To all whom it may concern:

Be it known that I, JOSEPH MALICKI, a citizen of the United States, residing at Chicago, in the county of Cook and State of Illinois, have invented certain new and useful Improvements in Closure Fasteners, of which the following is a specification.

This invention relates to improvements in closure fasteners, and has reference more particularly to that type of fastener employing a pin as the main element of the fastening means.

The chief objects of the invention are, to provide a very simple and efficient closure fastener, wherein the closure is effectively locked in place by the simple operation of driving a fastening pin into closure locking position, and to provide a closure fastener employing a locking pin, wherein the latter when forced into operative relation to the parts engaged thereby shall be automatically rendered incapable of accidental displacement, but may be withdrawn with the aid of suitable tools whenever it is desired or necessary to remove the closure.

My invention, its novel structural features, mode of action, and advantages will be readily understood by those skilled in the art from the following detailed description, taken in connection with the accompanying drawing wherein I have illustrated one practical form and application of the invention, and in which—

Fig. 1 is an inner side elevation of a portion of the hollow frame or casing of a lifting jack, showing an opening therein, a closure for said opening, and my improved closure fastener applied thereto;

Fig. 2 is a cross-sectional detail on the line 2—2 of Fig. 1; and

Fig. 3 is an isolated detail of the locking pin as the same appears before it is driven into closure fastening position.

Referring to the drawing, 5 designates a fragmentary portion of one side wall of a jack frame or casing, in which is formed an opening 6 lying opposite the pawls and pawl-controlling mechanism (not shown) of the jack and through which the latter may be inspected and gotten at whenever required. 7 designates a removable cover-plate for the said opening formed with a countersunk margin 8 on its inner side fitting the margin of the opening 6. In the structure herein shown, one vertical por-

tion of the margin of the opening is formed by an edge portion of the rear wall 9 of the jack frame which lies at a right angle to the wall 5; and through the wall 9 is formed a horizontal hole 10 of a size to fit a locking pin 11.

On the inner side of the closure 7 is cast a lug 12, through which is formed an inclined hole 13, the outer and lower end of which lies directly opposite to the hole 10 in the frame, and is preferably beveled or chamfered, as shown at 13'.

On the opposite edge of the closure plate 7 are cast a pair of hook-shaped lugs 14 which, when the closure is applied, engage 70 behind the adjacent vertical margin of the opening, and thus secure the cover-plate against removal on that side.

The cover-plate is applied by first engaging the hook lugs 14 with the contiguous 75 margin of the opening, and then pressing the cover-plate into full engagement with its seat. The pin 11, in the straight form shown in Fig. 3, is then driven into and through the registering horizontal and inclined holes 80 10 and 13 of the frame and lug, respectively. As the pin is driven in through the hole 13, it necessarily assumes the bent form illustrated in Fig. 1, as a result of which it is automatically locked in closure fastening 85 position against any possibility of accidental displacement, or removal by purely manual manipulation. However, whenever it is necessary to retract the pin, this can readily be accomplished by inserting an 90 edged tool, such as a chisel, under the head 11' of the pin and prying the latter away from the frame sufficiently to enable it to be engaged by a claw-bar and fully retracted; in which operation the pin is automatically brought back to a substantially 95 straight condition.

While I have illustrated and described one particular application of my improved closure fastener, it will be understood that 100 the fastening feature is capable of general application in many other situations where a simple and efficient automatic lock is required not requiring the use of a key to release the closure. The device is especially 105 useful where applied to articles which are moved about from place to place and may be deposited in any of various positions, since there is no possibility of the locking pin dropping out of place even though the 110

article to which it is applied should be deposited in a position where gravity would otherwise cause the pin to fall out.

I claim—

- 5 1. The combination with a member formed with an opening and a hole therein adjacent to the margin of said opening, of a closure fitted to said opening and itself formed with a hole registering with the hole in said member and disposed at an angle to the latter, and a straight fastening pin 10 driven through said holes and thereby bent into self-locking engagement with the latter.
- 10 2. The combination with a frame member formed with an opening and a hole therein adjacent to the margin of said opening, of a closure fitted to said opening and having on one side thereof a lug formed with a hole registering with the hole in said frame

member and inclined relatively to the latter, and a straight fastening pin driven through said holes and thereby bent into self-locking engagement with the latter.

20 3. The combination with a hollow frame member formed with an opening in a wall 25 thereof and a hole therein adjacent to a marginal portion of said opening, of a cover-plate fitted to said opening, said cover-plate having on its inner side one or more hook lugs engaged with the opposite 30 marginal portion of said opening and also a fastening lug formed with a hole registering with the hole in said frame member and inclined relatively to the latter, and a straight fastening pin driven through said 35 holes and thereby bent into self-locking engagement with the latter.

JOSEPH MALICKI.
